UNITED STATES PATENT OFFICE.

FRANCIS FREDERICK ROBERTS, OF DENVER, COLORADO.

FOOT-GUARD FOR FROGS OR THE LIKE.

SPECIFICATION forming part of Letters Patent No. 566,096, dated August 18, 1896.

Application filed December 4, 1895. Serial No. 571,002. (No model.)

To all whom it may concern:

Be it known that I, FRANCIS FREDERICK ROBERTS, a citizen of the United States, and a resident of Denver, in the county of Arapahoe and State of Colorado, have invented certain new and useful Improvements in Foot-Guards for Switch-Frogs, of which the following is a specification, reference being had to the accompanying drawings, forming a part thereof, 10 in which similar letters of reference indicate corresponding parts.

This invention relates to what are known as the "frogs" of railway-switches, and the object thereof is to provide a guard which is 15 adapted to prevent the serious and sometimes fatal accidents which frequently result by reason of the foot becoming fastened therein.

The invention is fully disclosed in the following specification, of which the accompanying drawings form a part, in which—

Figure 1 is a plan view of one form of my improvement, showing also the application thereof; Fig. 2, a section on the line 3 3 of Fig. 1; Fig. 3, a longitudinal section on the line 2 2. Fig. 4 is a plan view of a modified form of construction, and Fig. 5 a section on the line 5 5 thereof.

In the drawings forming part of this application, A and B represent the adjacent rails 30 of a railway-switch, which converge to a point between which is formed a narrow triangular space C, which is called the "frog," and in the practice of my invention I place within this space a plate D, which is of the general form 35 thereof, and which is supported by a longitudinal plate-spring E, which is secured to the bottom thereof, and the ends of which are curved downwardly, as shown at F, so as to form spring-supports for the plate D, and 40 beneath the spring E, and centrally thereof, is preferably placed a supplemental longitudinal spring G.

The plate-spring E is provided near each end with a transverse slot H, through which 45 passes a bolt or pin K, which passes through or is secured in the plate D, and secured to said pin or bolt, or to the lower end thereof, and below the plate-spring E, is a spiral spring L, the opposite ends of which are secured to the opposite sides of the plate-spring E, which is wide enough to extend entirely across the space between the rails A

and B. As thus constructed, it will be seen that the plate D, which may be composed of wood or any desired material, is supported 55 at about a level with the tops of the rails A and B, and said plate, by reason of the slots in the plate-spring E and the springs L, secured to the pins K, is capable of slight lateral movement, the object of this being to 60 provide means whereby, when the rims of the car-wheels are passing, the plate D will yield, so as to provide a space therefor between said plate and the rails A and B. This device is perfectly adapted to accomplish the object 65 for which it is intended, and the accidents hereinbefore referred to will be rendered impossible thereby.

In Figs. 4 and 5 I have shown a modified form of construction in which the plate D of the guard is stamped from a piece of sheet metal, and is supported by a longitudinal spring F, as hereinbefore described, the central portion of which is secured to the central portion of the plate D, and in this form 75 of construction the plate D and the spring F will yield to provide a space for the rims of the car-wheels, and, as will be observed, the plate D is provided with longitudinal flanges at each side which extend beneath 80 the heads of the rails A and B, and which serve to prevent the displacement of the guard and to retain the same in the proper position. It will be understood that the spring F in this form of construction may be bolted or otherwise 85 secured to cross-ties, and it will be observed that the plate-spring F in the construction shown in Figs. 1, 2, and 3 also extends on each side beneath the overhanging heads of the rails A and B.

My invention is not limited to the exact form, construction, and arrangement of the various parts herein shown and described, and I therefore reserve the right to make all such alterations therein and modifications 95 thereof as fairly come within the scope of the invention.

Having fully described my invention, its construction and operation, I claim and desire to secure by Letters Patent—

1. A foot-guard, for the frogs of railways which comprises a plate which is supported therein at approximately a level with the tops of the rails, said plate being supported

by springs and capable of lateral movement, substantially as shown and described.

2. A foot-guard for the frogs of railways comprising a plate adapted to be secured therein, said plate being of the same form as the space in the frogs, and being supported on a spring-plate, in which are formed transverse slots, through which project pins or bolts secured to said plate, and to the lower ends of to which are secured springs, the opposite ends

of which are secured to the sides of said plate-spring, substantially as shown and described.

In testimony that I claim the foregoing as my invention I have signed my name, in presence of the subscribing witnesses, this 23d 15 day of November, 1895.

FRANCIS FREDERICK ROBERTS.
